UNITED STATES PATENT OFFICE

ISAAC DAEHLIN, OF FREEPORT, ILLINOIS

COMBINATION INSTRUMENT

Application filed January 2, 1929. Serial No. 329,834.

The present invention is directed to improvements in combination instruments.

The primary object of the invention is to provide an instrument so constructed that it 5 can be effectively used as an inside or outside caliper.

Another object of the invention is to provide a device of this kind wherein the center of an object can be quickly and accurately 10 determined.

Another object of the invention is to provide an instrument of this nature constructed in such manner that it can be used as a pencil compass.

15 Another object of the invention is to provide a device of this kind which is simple in construction, efficient in operation, durable, and one which can be manufactured at a small cost.

20 Another object of the invention is to provide a device of this character which is easily and quickly adjustable for performing various functions, the construction being such that it can be conveniently folded when 25 not in use.

With these and other objects in view, this invention resides in the novel features of construction, formation, combination and arrangement of parts to be hereinafter more 30 fully described, claimed and illustrated in the accompanying drawings, in which:—

Figure 1 is a side elevation of the device.

Figure 2 is an edge view.

Figure 3 is a reverse side view showing the 35 legs in position for attachment of a pencil.

Figure 4 is a sectional view on line 4—4 of Figure 1.

Figure 5 is a sectional view on line 5—5 of Figure 3.

40 Referring to the drawings, 1 designates a bar having a longitudinal slot 2 formed therein, said bar having its lower end terminating in a centering point 3, the upper end of said bar having a horizontally disposed flange 4 carried thereby in which is formed a gauge opening 5. The bar is provided with a plurality of gauge openings 6, varying in size in order that the size of rivets or bolts can be 45 quickly and accurately determined.

50 Engaged on the bar 1 is a U-shaped slide 7,

the spaced plates 8 of which engage opposite sides of the bar, said slide being retained upon the bar by a bolt 9 which has its flat portion 10 slidable in the slot 2, said bolt passing through the side plates 8. A winged nut 11 is 55 engaged upon the bolt in order that the slide can be held in adjusted position upon the bar 1, when the occasion requires, it being obvious that when the nut is released the slide can move freely.

Having their upper ends pivotally connected to the bolt 5 are legs 12, said legs being arranged upon opposite sides of the slide in order that they can freely pass each other 60 when swung in reverse directions.

65 A pair of links 13 are provided and have their lower ends pivotally secured to the opposite sides of the lower end of the bar 1 by a pin 14 whereby the links may be pivoted on the single pin as an axis, the upper ends of 70 said links being pivotally connected intermediate the ends of the legs 12, as at 15.

One of the legs 12 is graduated, as at 16, so that the same can be used as a rule, it being 75 of course understood that the other leg is likewise graduated.

The bar 1 is marked with suitable graduations 17 and 17' which cooperate, respectively, with the slide in order that the outside and inside diameters of an object can be quickly observed when the lower ends of the legs are 80 properly set with respect to the object being gauged. Any well known system of graduation may be used for this purpose.

The lower ends of the legs 12 are curved 85 slightly and terminate in points 18, and owing to this curvature the points will at all times be in position for accurate disposition upon the article gauged.

As shown in full lines in Figure 1, the legs 12 are in position to permit the instrument to be used as an outside caliper, and to also center the point 3 to accurately determine the center or longitudinal axis of the object being gauged. Since the legs 12 are pivotally mounted upon opposite sides of the bar 1 they may be swung past each other to assume the position, as shown in dotted lines in Figure 1, and at which time the instrument may 90 be used as an inside caliper.

Obviously when the legs are swung for use the slide will move upon the bar, and a reading can be made of the graduations to denote the diameter of the object, the upper edge of said slide serving as an indicator.

As shown in Figure 3 both legs 12 have been swung into parallel relationship upon one side of the bar 1, and when in this position the instrument can be effectively used as a compass. When this is desired a resilient clamp 19 is engaged upon either of the legs 12 and held clamped thereon by the bolt 20, the point 3 obviously serving as a pivotal point for the instrument. The arms of the clamp are provided with jaws 21 for clamping a pencil 22, the point of which being arranged adjacent the point 18 of the leg. If desired each leg may be supplied with a pencil holding clamp, said clamps being necessarily secured to the leg at different elevations in order that a double line can be drawn.

It is thought that the operation and advantages of the herein described invention will be apparent to those skilled in the art without further description.

The bar 1 is also provided with graduations 23 upon its reverse side, in order that when the instrument is laid on the paper and the slide 7 is clamped or set opposite a selected graduation lines can then be drawn along the outer edges of the legs 12. The instrument is then removed and the disconnected ends of the lines, due to presence of the slide 7, can be completed. In this manner angles can be drawn for 10° to 165°.

What is claimed is:—

1. An instrument of the class described comprising a bar, a slide movable longitudinally of the bar, legs having their upper ends pivotally connected with the slide and arranged upon opposite sides of the bar, and links pivotally connecting the bar and legs, said links being pivoted to the bar on opposite sides and about a single axis, said legs and links being adapted to move past each other to opposite sides of the bar to adjust the legs to measure inside or outside dimensions.

2. An instrument of the class described comprising a bar having a longitudinal slot therein, a slide, a bolt engaged with the slide and movable in the slot, legs disposed on opposite sides of the bar and having one of their ends pivotally connected to the bolt, and links pivoted to the bar on opposite sides and about a single axis and pivotally connecting the bar and legs for moving the legs simultaneously during movement of the slide, said legs being swingable on said pivot bolt to pass each other and reverse their positions on opposite sides of the bar for measuring inside or outside dimensions.

3. An instrument of the class described comprising a bar having a longitudinal slot formed therein, a U-shaped slide including side plates for engaging the opposite sides of

the bar, a bolt engaged in the plates and movable in the slot, a pair of legs arranged upon opposite sides of the bar and having their upper ends pivotally connected with the bolt, said legs being curved outwardly at the free ends, and links pivotally connecting the bar and legs, said links being pivoted to the bar on opposite sides and about a single axis, said legs being adapted to be swung past each other to reversed positions on opposite sides of said bar to measure inside or outside dimensions.

In testimony whereof I affix my signature.

ISAAC DAEHLIN.
